UNITED STATES PATENT OFFICE.

NORMAN LIPSKY, OF NEW YORK, N. Y., ASSIGNOR TO GOLDEN LIGHTING FIXTURE CO., INC., A CORPORATION OF NEW YORK.

DESIGN FOR A LIGHTING FIXTURE.

Application filed April 29, 1927. Serial No. 21,795. Term of patent 3½ years.

To all whom it may concern:

Be it known that I, NORMAN LIPSKY, a citizen of the United States of America, and a resident of the city, county, and State of New York, have invented a new, original, and ornamental Design for a Lighting Fixture, of which the following is a specification, reference being had to the accompanying drawing, forming a part hereof.

In the drawings:

I claim:

The ornamental design for a lighting fixture substantially as shown.

NORMAN LIPSKY.
